VOLTAGE REGULATOR

Joseph F. Frese, Baltimore, Md., assignor to Monitor Controller Company, Baltimore, Md., a corporation of Maryland

Application November 2, 1934, Serial No. 751,238

2 Claims. (Cl. 171—229)

This invention relates to voltage regulators adapted particularly for use in connection with generators driven at variable speeds from car axles and adapted to charge storage batteries.

5 Carrying out the invention, I provide a carbon pile which is connected in series with the shunt field winding of the generator, spring-pressed means for applying pressure to the pile and a motor connected to the terminals of the generator armature for relieving the pressure on the pile to increase the resistance in the field circuit of the generator and thereby maintain a substantially constant voltage at the armature terminals after the voltage has increased to a predetermined 15 value suitable for charging the battery. More particularly, the invention relates to the mounting of the pile, to means for applying and relieving pressure to the pile at both ends simultaneously, to certain adjusting features, and to 20 means for preventing sudden movements of the pressure applying and relieving devices, the details and advantages of which will be clear from the following specification.

In the accompanying drawings,

25 Fig. 1 is a front elevation, partially cut away, of the regulator;

Fig. 2 is a section on the line 2—2 of Fig. 1;

Fig. 3 is a section on the line 3—3 of Fig. 1;

Fig. 4 is a section on the line 4—4 of Fig. 1;

30 Fig. 5 is a top plan view of the regulator;

Fig. 6 is a section on the line 6—6 of Fig. 1;

Fig. 7 is a section on the line 7—7 of Fig. 1, and,

Fig. 8 is a diagram of the circuit connections.

Referring to the drawings, *a* indicates a suitable 35 base adapted to be attached to an upright support, so that the base will lie in a vertical plane, by bolts or screws passing through holes *1* in the corners of the base. Brackets *b* and *b'* are secured to the upper part of the base near its opposite ends by bolts *2*, said brackets comprising flat plates which project forwardly from the base in vertical planes. In the upper parts of the bracket are arranged two parallel metal rods,

40 rods *3* and *4*, spaced horizontally apart from one another and below these are similar rods, *5* and *6*, spaced apart horizontally, but closer together than are the rods *3* and *4*. These rods are surrounded by tubes *3^a*, *4^a*, *5^a*, and *6^a*, respectively, of refractory insulating material, such as porcelain.

45 As shown in the drawings, the tubes are held in position on the rod by sheet metal cups *7* inserted in the ends of the tubes and cushioning springs *8* interposed between these cups and cups *9* on the inner sides of the brackets.

50 A carbon pile *C*, comprising a horizontal series

of circular discs *c* is arranged between the four rods, *3*, *4*, *5* and *6*, and rests upon the lower tubes *5^a* and *6^a*, the upper tubes serving merely to prevent displacement of the discs by jarring or while the regulator is being handled. The carbon discs *c* and *c²* at the ends of the pile are thicker than the intermediate discs *c* and are secured to metal terminal discs *10* and *11*, respectively. The terminal disc or plate *10* has a rearwardly projecting arm *10^a* connected by a flexible conductor *12* to a binding post *13* secured to and insulated from the base *a*, and the terminal disc or plate *11* has a similar arm *11^a* connected by flexible conductor *14* to binding post *15*.

55 A metal clamping disc *16* is secured to the terminal plate *10* and insulated from it by a disc of insulating material *17*, and a metal clamping disc *18* is secured to the terminal plate *11* and insulated from it by a disc of insulating material *19*. The details of these connections are the same at both ends of the pile, and those at the right hand end are illustrated in Fig. 4, where it is shown that the carbon disc *c* is connected to the terminal plate *10* by screws *20* passing through the carbon disc and into the plate, and the clamping disc *16* is connected to plate *10* by screws *21* which are insulated from the clamping plate.

60 The clamping discs *16* and *18* are movable simultaneously in opposite directions either to relieve or apply pressure to the pile by levers *d* and *e*, respectively, which swing in vertical planes and are connected together at their lower ends by a link *f*.

The lever *e*, as shown in Figs. 1, 3 and 5, is mounted on a pivot pin *22* which passes through spaced lugs *23* and *24* projecting from the inner side of the bracket *b* and has a forked upper end pivoted to a lug *18^a* which projects outwardly from the clamping plate *18*. The lower end of the lever is pivotally connected at *25* to one end *40* of the link *f*. The lever *d*, which is of the form shown in Fig. 7, has forked arms *26* at its upper end connected by a pivot pin *27* to the arms *28* of a yoke *g* which rests on horizontal surfaces of spaced supports *29* projecting from the inner face of bracket *b'*. This yoke has a threaded stem *30* which extends through an opening in the bracket and the stem is adjustably secured to the bracket by nuts *31* and *32*. The lever *d* is thus pivotally suspended at its upper end in the yoke and the yoke is adjustable toward and from the carbon pile along the horizontal surfaces of the supports *29*. Below the pivot pin *27*, the lever *d* is connected by a pivot pin *33* to a lug *34* projecting from the central part of the clamping 55

disc 16 and the lower end of the lever is connected to the link *f* by a pivot pin 35.

A flat rod *h* is connected at one end to the pin 35 and the other end of the rod is connected to a spring 36. The opposite end of the spring is connected to a threaded rod 37 which extends through an opening in the lower part of the bracket *b*. A thumb-nut 38 is provided on this rod for adjusting the tension of the spring. The 10 spring pulls the rod *h* to the left, and since this rod is connected to the lever *d* and also, through the link *f*, to the lever *e*, the tension of the spring will be applied to both levers. As the lever *d* is fulcrumed at its upper end and connected to the clamping plate 16 intermediate its ends and the lever *e* is fulcrumed between its ends, both clamping plates will be pressed against the pile by the tension of the spring, and if the rod *h* is moved to the right, both levers 20 will be rocked to relieve the pressure of the clamping plates against the pile.

The link *f* is movable in opposition to the spring to relieve the pressure on the pile by a motor comprising a magnet *M* having a coil 39 and pole-pieces 40 and 41 and an armature 42 pivoted at its center on a fixed shaft 43 and adapted to rock between the pole-pieces. The magnet is supported by frame *j* of non-magnetic metal secured to the base below the carbon pile 30 and having a hollow rectangular casing *j'* which fits over the pole-pieces and to which the pole-pieces are secured by bolts 44. The stud or shaft 43 is supported in the front side 45 of the casing *j'*, where it is secured by a set screw 46, and in a boss 47 on the frame *j*. A bell crank lever *k* has a sleeve 48 journaled on the stud 43, a part 48^a of this sleeve extending through an opening in the casing *j'* and being secured to the armature 42 by a pin 49, Fig. 1. A short arm 50 of the bell crank lever extends upwardly and carries a roller 51 which is adapted to engage a block 52 secured to the rear side of the link *f*. A longer arm 53 of the bell crank lever is pivotally connected to a link 54, the upper end of which is connected to a piston 55 in a dash pot cylinder 56. This cylinder is suspended from a lug 57 projecting from the bracket *b*, and has an adjusting screw 58 at its upper end for regulating the inflow and outflow of air to the cylinder.

50 When the motor armature moves from the position shown in Fig. 1 to a position in line with the magnet pole-pieces, the shorter arm of the bell crank lever bearing against the block 52 on the link *f*, moves the link to the right in opposition to the tension of the spring 36 and causes the levers *e* and *d* to rock and lessen the pressure of the clamping plates against both ends of the pile simultaneously, and as the magnet loses strength, the spring 36 moves these several parts 55 toward normal position and the levers simultaneously increase the pressure at the ends of the pile. The air dash pot prevents any sudden movement of the levers, which might be injurious to the pile.

65 As the magnet coil is of copper wire, the resistance of which changes with increase of temperature, a resistance coil 65 of much higher resistance and of wire having no temperature coefficient is placed in series with the magnet coil 70 to cut down the current so that the resistance of the coil is only a small percentage of the total resistance in circuit and the temperature of the magnet coil is not greatly affected by the current flowing through it.

75 In Fig. 1, 60 and 61 indicate terminals to be

connected in circuit with the field of the generator and 62 and 63 indicate terminals to be connected across the armature terminals of the generator. As shown in Figs. 1 and 2, terminal 60 is connected by conductor 64 to binding post 13 and thence by flexible conductor 12 to terminal disc 10 at the right hand end of the pile. Terminal 61 is connected by conductor 66 to binding post 15 and thence by flexible conductor 14 to terminal disc 11 at the left-hand end of the pile. Terminal 63 is connected by conductor 67 to one terminal of the resistance coil 65, and the other terminal of said coil is connected by conductor 68 to the magnet coil 39, and the return connection 69 from the magnet coil is connected to 15 terminal 62.

In the diagram, Fig. 8, *M* indicates the motor of the voltage regulator, the coil 39 of which is connected to the terminals of the armature 70 of a generator *G* through resistance 65, and *C* 20 indicates the carbon pile connected in series with the shunt field 71 of the generator. The charging circuit 72, indicated in heavy lines, extends from one terminal of the generator armature through normally open switch 74 and coil 75 of 25 reverse current relay *N* to the battery 73 and thence to the opposite terminal of the generator armature. The relay *N* cooperates with a contactor *O* to close the charging circuit at the switch 78 when the generator voltage reaches a 30 pre-determined value and to open the charging circuit when the generator voltage falls below said value by reason of slowing down of the generator. The reverse current relay and its connections are described in my Patent No. 1,973,804, 35 dated September 18, 1934 and form no part of the present invention.

The discs of the carbon pile, with the exception of the end discs which are secured to the metal terminal discs and clamping plates, are 40 all supported by the lower tubular insulators 5^a and 6^a, which keep the discs in alinement. Pressure is applied equally at both ends of the pile by the spring 36, and this pressure can be varied as desired by turning the thumb-nut 38, to adjust the resistance of the pile. As the voltage at the terminals of the generator armature rises with increased speed of the generator, the armature of the voltage regulator applies pressure to the lower ends of the levers *d* and *e* in opposition 50 to the tension of the spring 36 and the levers operate to reduce the pressure on the pile, thus increasing the resistance in the shunt field circuit of the generator and controlling the voltage of the generator accordingly. To compensate for 55 wear on the faces of the carbon discs composing the pile which may result from any cause, such as vibration of the car or arcing between the discs, the yoke *g* in which the lever *d* is fulcrumed may be adjusted toward the pile, and this will 60 cause the clamping plate 16 to be similarly adjusted. By providing means at both ends of the pile for applying and relieving pressure on the carbon discs the discs throughout the pile loosen 65 from one another more readily than they would if the discs were held between a fixed stop at one end and a pressure applying means at the opposite end.

What I claim is:

70 1. In a voltage regulator, a suitable base, a carbon pile supported in horizontal position thereon, clamping members at the ends of the pile, vertically arranged levers, one lever pivotally supported between its ends and having its upper end connected to one of said members and the other 75

lever pivotally supported at its upper end and connected intermediate its ends to the other clamping member, a link connecting the lower ends of said levers, a spring for moving said link in one direction, to apply pressure to the pile, and a motor for moving said link in the opposite direction to relieve pressure on the pile.

2. In a voltage regulator, a suitable base, brackets projecting from the base, horizontally arranged rods extending between said brackets and

having refractory coverings, springs interposed between the ends of said coverings and said brackets, a carbon pile composed of loosely arranged discs resting on edge on said coverings, similarly mounted rods and coverings above said first mentioned rods for preventing displacement of said discs, spring-pressed means for applying endwise pressure to said pile and a motor for actuating said means to relieve pressure on the pile.

JOSEPH F. FRESE. 10
